UNITED STATES PATENT OFFICE.

THOMAS J. CRUMPTON, OF COALINGA, CALIFORNIA.

AIR-JET LIFT.

1,186,379.

Specification of Letters Patent.

Patented June 6, 1916.

Application filed July 7, 1914. Serial No. 849,542.

To all whom it may concern:

Be it known that I, THOMAS J. CRUMPTON, a citizen of the United States, residing at Coalinga, in the county of Fresno and State of California, have invented a new and useful Air-Jet Lift, of which the following is a specification.

This invention relates to a new and useful air jet lift, and aims to provide an ejector 10 of novel and improved construction, whereby its utility is enhanced.

Another object of the invention is to provide a check valve assembled with the ejector in a unique manner, for supporting 15 the column of water or other liquid when the device is idle.

With the foregoing and other objects in view which will appear as the description proceeds, the invention resides in the combination and arrangement of parts and in the details of construction hereinafter described and claimed, it being understood that changes in the precise embodiment of 20 the invention herein disclosed, can be made within the scope of what is claimed, without departing from the spirit of the invention.

In the drawings accompanying this specification and forming a part thereof, the 30 preferred embodiment of my invention is illustrated.

In said drawings:—Figure 1 is a view in longitudinal section of my improved air lift pump. Fig. 2 is a bottom view thereof. 35 In carrying out the present invention, there is provided an upright cylindrical casing or shell 4, which is provided with a longitudinal eccentric bore 5 of large diameter, and with a second or supplemental longitudinal eccentric bore 6 of relative small diameter and disposed at the thick side of the casing or shell 4 formed by the eccentric bore 5. The upper end of the bore 5 is threaded, as at 7, and the said bore 5 is provided intermediate its ends with a frusto-conical portion 8, the bore 5 being of smaller diameter above the portion 8, than below the same. The casing 4 is further provided with an inner annular ledge or rib 9 at the 45 lower end of the bore 5, for providing a contracted inlet opening 10 having a flared mouth 11.

An inspirator sleeve or tube 12 is fitted snugly in that portion of the bore 5 above 50 the portion 8 thereof, and threadedly en-

gages the internal screw threads 7 of the casing 4. The upper portion of the sleeve 12 projects or protrudes above the casing 4, and is provided with internal screw threads 13 for the attachment of the sleeve 12 to the lower end of the well casing or tubing. Thus, the sleeve 12 serves to couple the casing 4 to the lower end of the well casing (not shown), whereby the parts may be readily assembled and separated. The bore 65 of the sleeve 12 is tapered from the ends of the said sleeve to an intermediate point, to thereby provide a restricted portion between the ends of the sleeve 12, and the lower flared portion of the bore of the sleeve 12 is 70 flush with the portion 8 of the bore 5.

A spider-shaped valve seat 14 is threaded into the opening 10, and its hub is provided with an aperture 15 through which an upwardly projecting air or fluid 75 nozzle 16 passes. The nozzle 16 is arranged axially within the bore 5, and the lower protruding end of the nozzle 16 is connected by means of the pipe sections 16' to the lower end of the supplemental bore 6, as 80 at 17, whereby an air, steam or pressure fluid pipe attached to the upper end of the bore 6, will be brought into communication with the nozzle 16. The nozzle 16 includes the body portion 17' of uniform diameter 85 passing through the aperture 15, and the tapered tip 18 which projects into the lower portion of the sleeve 12, and which terminates immediately within the restricted or contracted portion of the sleeve 12 intermediate the tapered portions of the bore of the sleeve 12.

The tip 18 provides a lower shoulder 19, and a check valve 20 is slidable upon the body portion 17' of the nozzle 16 to normally rest upon the valve seat 14 for closing the passages therethrough. A spiral wire spring 21 is disposed between the valve 20 and the shoulder 19 for normally seating the valve, and for enabling the valve to unseat after the suction within the bore 5 has reached a predetermined degree. The valve 20 in being normally closed, will support the column of water or other liquid thereabove within the well casing, when the device is idle, the valve 20, which is of disk form is of smaller diameter than the large portion of the bore 5 below the frusto-conical or tapered portion 8, in order that when the valve 20 is unseated, the water, oil, 100 105 110

or other liquid may readily pass the periphery or margin of the valve in flowing upwardly.

In operation, supposing the upper end of the inspirator sleeve 12 be attached to the lower end of a well casing or pipe, when the well casing or pipe is lowered into the Artesian or deep well, until the ejector is lowered or immersed in the oil, water, or other liquid which is to be elevated, the air, steam or other pressure fluid is supplied to the bore 6 by a suitable pipe (not shown) and the air or other pressure fluid in being discharged from the nozzle 16 at the restricted portion of the sleeve 12, will create a suction through the lower portion of the sleeve 12 and the bore 5. Thus, the tendency to create a vacuum in the lower portion of the sleeve 12 and bore 5 will lift the liquid into the ejector, the valve 20 being automatically unseated, and the liquid will be drawn upwardly into the sleeve 12, and in passing the restricted portion of the sleeve 12 will be forcibly raised or elevated into and through the well casing or pipe. It is to be noted that the lower portion of the sleeve 12 is tapered to enable the liquid to be drawn upwardly properly by the discharge of the pressure fluid while the upper portion of the sleeve 12 is tapered to enable the liquid to be properly forced upwardly. It is thus desirable to discharge the pressure fluid at the contracted portion or zone of the inspirator sleeve, to increase the efficiency of the ejector, and to reduce any reacting or counter-acting eddies to a minimum.

Having thus fully described my invention, what I claim is:—

An ejector embodying a vertical cylindri-

cal casing having a longitudinal eccentric bore of relatively large diameter extending from end to end, and a second longitudinal eccentric bore at the thick side of the casing and of relatively small diameter, a relatively long inspirator sleeve fitted snugly in the first mentioned bore, said sleeve being threaded in the upper end of the first mentioned bore and projecting below the central portion of said bore, the upper end of said sleeve projecting above the casing for attachment to a pipe, the bore of the sleeve being tapered from its ends to an intermediate point to provide a constricted portion at said point, the casing being provided at the lower end of the first mentioned bore with an inner annular rib forming an inlet opening having a tapered mouth, a spider-shaped valve seat threaded within said rib, a nozzle projecting upwardly through the hub of said valve seat and having its tip disposed within said constricted portion of the inspirator sleeve, said nozzle having a downwardly facing shoulder above said valve seat, a valve disk slidable upon said nozzle under said shoulder and seatable upon the valve seat, a spiral spring having its larger end seated upon said valve disk and having its smaller end seated upwardly against said shoulder, and a pipe connecting the lower end of said nozzle and the lower end of the second mentioned bore.

In testimony that I claim the foregoing as my own, I have hereto affixed my signature in the presence of two witnesses.

THOMAS J. CRUMPTON.
